(57) **CLAIM**

We claim the ornamental design for a current transformer body, as shown and described.

DESCRIPTION

FIG. 1 is a side elevation view of a current transformer body showing the present invention in a “closed” position. FIG. 2 is a side elevation view of the side opposite that shown in FIG. 1.

FIG. 3 is an elevation view from the left side of FIG. 1.

FIG. 4 is an elevation view from the right side of FIG. 1.

FIG. 5 is a plan view from the top of FIG. 1.

FIG. 6 is a plan view from the bottom of FIG. 1.

FIG. 7 is an elevated perspective view from the upper left of FIG. 2.

FIG. 8 is an elevated perspective view from the upper right of FIG. 2.

FIG. 9 is a side elevation view similar to FIG. 1 of a current transformer body showing the present invention in an “open” position.

FIG. 10 is a side elevation view of the side opposite that shown in FIG. 9.

FIG. 11 is an elevation view from the right side of FIG. 9.

FIG. 12 is an elevation view from the left side of FIG. 9.

FIG. 13 is a plan view from the bottom of FIG. 9.

FIG. 14 is a plan view from the top of FIG. 9.

FIG. 15 is an elevated perspective view from the upper left of FIG. 10; and,

FIG. 16 is an elevated perspective view from the upper right of FIG. 10.

The current transformer body of the present invention is movable between the “open” and “closed” positions.

The broken line showing of current transformer body is for illustrative purposes only and forms no part of the claimed design.
